UNITED STATES PATENT OFFICE

2,421,795

ARMATURE BRUSH

Frank G. Majer, Berwyn, Ill., assignor to International Harvester Company, a corporation of New Jersey

Application February 8, 1945, Serial No. 576,809

2 Claims. (Cl. 171—325)

1

This invention has to do with electrical conductor brushes of the type used in conjunction with slip rings or commutators upon the rotatable armature of dynamo-electric machines, and the general object of the invention is the provision of brush components presenting a novel shaped armature contacting surface particularly adapted to retain its uniformity of contact with the armature.

Conventional brushes of the present class have a dimension between the leading and trailing edges thereof, or circumferentially of the armature, that is a compromise between a short dimension which tolerates partial dropping of the brush into low areas of a worn armature or a longer dimension which sometimes causes the brush to be cocked by the transverse force applied thereto by the rotating armature. Either of these conditions is undesirable for each causes sparking to occur between the brush and armature. Making the brush thin by decreasing the dimension between the leading and trailing edges to diminish the likelihood of cocking increases the tendency of the brush to bump against the edges of pits and the like which more frequently develop on commutators where the commutator bars and the insulation therebetween wear away unevenly. Thickening the brush by increasing the distance between the brush leading and trailing edges to avoid the disadvantages of the thin brush, incurs the above mentioned tendency to cock. In small dynamo-electric machines an acute problem has existed because the dimension range for a brush sufficiently thin to avoid the cocking contingency borders on or overlaps the dimension range wherein the brush is so thin as to ride irregularly over a worn surface complementary thereto on the armature. Under these circumstances the thickness of the brush between its leading and trailing edges becomes undesirably critical or even reaches a stage where it is impossible to select a thickness avoiding both of the undesired conditions.

A more specific object of the invention is the provision of a novel brush employing a thin planar formation having an end surface for contacting the cooperative current conducting surface of the armature while extending axially thereof, together with rib-like formation means projecting transversely of said planar formation, and such rib-like formation means reaching to the end of the brush which contacts the armature for preventing the armature contacting surface on the planar formation from bumping against the edges of armature surface depressions while

2

at the same time being sufficiently detritable to wear into conformity with the armature surface instead of causing the brush to cant or cock under the influence of the force applied thereto by the rotating armature.

The above and other desirable objects inherent in and encompassed by the invention will be more readily apparent upon reading the ensuing description with reference to the annexed drawings, wherein:

Figure 1 is a perspective view of a brush structure constituting a preferred embodiment of the invention and shown in operating relation with an armature commutator of a dynamo-electric

15 machine; and

Figure 2 is a transverse sectional view taken on the line 2—2 of Figure 1.

With continued reference to the drawings, the brush 11 is shown in conjunction with an armature commutator 12 of which only a few of the commutator bars 13 are shown in full lines. These commutator bars are isolated electrically from one another by the usual intervening layers 14 of insulating material. A conducting periphery 25 of the armature for being borne against by the brush 11 in current conducting relation therewith is formed by the radial outer peripheries of the commutator bars 13.

The upper end portion 15 of the brush constitutes a holding portion which is adapted to be anchored in a brush holder device not shown. A groove 16 within the holder end portion 15 is for cooperating with a brush holder instrumentality in the manner well known in the art.

35 The brush 11 may be formed conventionally by being molded into shape from minute carbon particles or such particles having metallic particles mixed therewith. Regarding the brush with reference to the direction of rotation of the

40 armature with respect thereto, as indicated by the arrow in Figure 1, such brush has a leading face 17, a trailing face 18 and opposite flank surfaces 19 and 21. Two cavities 22 and 23 are formed in the lower end portion. These cavities

45 are formed at the intersections of the flank surfaces 19 and 21 with the leading face 17 of the brush and extend lengthwise of the brush completely to the lower end thereof. Said cavities are also spaced from one another laterally of the

50 brush to leave a rib-like formation 24 therebetween. This rib-like formation 24 registers with a median line *a* (Figure 2). It is apparent in Figure 2 that the cavities 22 and 23 leave a planar formation 25 at the trailing face in the lower end 55 portion of the brush structure. This planar

formation and the formation 24 projecting laterally therefrom may be likened to intersecting free-ended ribs. The free ends of the rib 25 are the portions shown most remotely from the line a—a in Fig. 2 while the free end of the rib 24 is at the edge 26. The lower ends of the ribs or planar formations 24 and 25 bear complementally upon the armature periphery in current conducting relation therewith and stabilize the brush structure with respect thereto. Considering the brush structure with reference to the assumed direction of rotation of the armature, the leading edge of the armature-engaging face on the lower end of such brush structure has one component 27 at the forward edge of the formation 24 and other components 27 and 28 at the forward edge of the formation 25. The trailing edge 29 of the armature engaging face is at the trailing face of the formation 25. That portion of the armature-engaging face upon the rib 24 at the lower end of the brush constitutes a free-ended area of which the free end is at the edge 26.

It is the function of the rib 24 to extend the armature engaging face of the brush a sufficient distance circumferentially of the armature for causing the brush to ride smoothly over the armature surface and prevent the leading edge of the brush from dropping into and striking the edges of worn or depressed portions within the armature surface after it has become worn in use. In this respect the rib 24 has the effect of thickening the brush circumferentially of the armature. However, because of the rib 24 being thin transversely of the brush median line, the detritable material from which the brush is fabricated is adapted to wear away sufficiently rapidly at the armature engaging face of this rib by the concentration of force upon this face, pursuant to any tendency for the brush to cock by the force applied thereto circumferentially of and by rotating the armature to cause the brush face to conform to the armature and prevent cocking. The thin rib 24 therefore adapts the armature engaging surface of the brush to wear into conformity with the armature periphery instead of causing an edge of the brush to be slightly lifted from the armature should the brush and/or its holder (not shown) have a tendency to cock.

Having thus described the preferred embodiment of the invention with the view of clearly illustrating the same, I claim:

1. An electric current conducting brush comprising a holder end portion and an opposite end portion for engaging an electrical conductor periphery of an electrical machine armature during relative movement between the brush and armature in the direction of a median line directed transversely of the brush, the opposite end portion of said brush including a relative thin detritable electrical conductor rib-like formation 10 projecting endwise of the brush from the holder end portion and disposed transversely of said median line, said opposite end portion also including a single detritable electrical conductor rib disposed transversely of said rib-like formation 15 in registry with said median line and extending lengthwise of the brush from its holder end portion, and said rib-like formation and said rib having free-ended faces at the opposite end of the brush and adapted to bear complementally on the armature periphery in current conducting relation therewith.

2. An electrical conductor brush structure having a holder end, an opposite end for engaging an electrical conductor periphery of an electrical machine armature, oppositely disposed leading and trailing faces extending lengthwise of the structure and oppositely disposed flank surfaces extending lengthwise of the structure and reaching between the leading and trailing faces, and said structure containing cavities at the intersections of said surfaces with one of said faces, said cavities being spaced from the holder end of the structure while communicating with the opposite end thereof and being spaced from one another transversely of the one face to leave a rib formation therebetween having a free edge extending lengthwise of the structure to the armature periphery engaging end thereof.
